GAS TURBINE ROTOR COOLING MEANS

Jules André Norbert Galliot, London, England

Application February 24, 1947, Serial No. 730,446
In Great Britain February 25, 1946

13 Claims. (Cl. 60—35.6)

1

This invention relates to gas turbines such as are employed for aircraft propulsion and like purposes, and comprising for example a peripherally bladed rotor secured upon a shaft which drives a compressor feeding air to one or more combustion chambers furnishing hot gases to drive the peripheral blades of the rotor.

The main object of the present invention is to provide an improved gas turbine so arranged and constructed that its rotor affords passage for cold air flowing to the compressor intake whereby the rotor is effectively cooled, together with its blades, shaft and bearings.

A secondary object of the invention is to provide an improved gas turbine having a rotor fitted with external blades driven by hot gases and internal vanes forcing cold air axially to a compressor feeding a combustion chamber which furnishes the hot gases, said blades and vanes being in thermally conductive relation to transmit heat from said blades to said vanes for dissipation in the cold air passing between said vanes.

A further object of the invention is to provide an improved gas turbine having an apertured rotor which constitutes a primary element of an auxiliary compressor forcing the air admitted through the rotor apertures to the intake of the main compressor driven by the turbine shaft.

Another object of the invention is to provide an improved gas turbine having an apertured rotor and an air compressor mounted towards opposite ends of a driving shaft, with a tubular casing around the shaft, the air admitted through the rotor apertures flowing along the interior of the casing to the intake of the compressor.

A still further object of the invention is to provide an improved gas turbine having an apertured and externally bladed rotor and a main compressor mounted towards opposite ends of a driving shaft, with a tubular casing around the shaft, an axial-type compressor inside the casing, and an annular series of combustion chambers spaced around the casing, the air admitted through the rotor apertures being forced along the interior of the casing through the axial-type compressor to the intake of the main compressor which delivers compressed air to the combustion chambers, and the latter furnishing hot gases to drive the external blades of the rotor.

A specific object of the invention is to provide an improved gas turbine for jet-propelled aircraft, with or without an airscrew driven by the turbine shaft, in which an apertured turbine rotor and its air compressor are mounted towards op-

2

posite ends of the turbine shaft, with an annular series of combustion chambers spaced around the shaft, the air admitted through the rotor apertures flowing to the intake of the compressor which delivers compressed air to the combustion chambers, the latter furnishing hot gases to drive external blades upon the turbine rotor, and the gases exhausted from the turbine being collected to form a propulsive jet.

10 Other objects and advantages of the invention will hereinafter appear from the following description, given with reference to the accompanying drawings, in which:

Fig. 1 is a half sectional elevation of the turbine;

Fig. 2 is a partial development of the rotor on a larger scale, showing six of the turbine blades;

Fig. 3 is a partial end-view of the rotor, showing six of the external turbine blades as well as 20 the corresponding internal vanes forming the primary element of an axial-type compressor;

Fig. 4 is a detail on a larger scale, showing a modified form of platform;

Fig. 5 is a partial end-view of the rotor hub 25 mounted upon the turbine shaft, showing the method of assembling the roots of the compressor vanes;

Fig. 6 is a half-section of the rotor hub, seen at right angles to Fig. 5 taken at the center line;

30 Figs. 7 and 8 are part-sectional views, showing an exhaust manifold for feeding a propulsive jet for aircraft;

Fig. 9 is a half sectional elevation of a modified turbine arranged to drive an airscrew for aircraft propulsion and also to deliver a jet for the same purpose; and

Fig. 10 is a half sectional elevation of another modification of turbine arranged for pure jet propulsion of an aircraft.

40 In the construction illustrated in Fig. 1, the turbine shaft 10, driven by a rotor 11 at the forward end, drives an air compressor 12 mounted towards the other end of the shaft; this compressor feeds a number of combustion chambers 13 spaced around the shaft, each chamber being provided 45 with fuel-injection means 13a and delivering the hot gases of combustion through guide vanes 14 to the external blades 15 of the turbine rotor.

The central portion of the rotor 11 is apertured by providing it with spokes or webs which 50 are shaped as helicoidal vanes 16 (see Figs. 2, 3, 5 and 6) to constitute a primary element of an axial-type compressor; the cold air may be admitted directly to the turbine rotor 11 by a flared 55 inlet, opening in the direction of forward flight.

A shaft bearing, which is preferably of the self-aligning thrust-resisting type, is carried by radial arms or webs 18 inside the turbine stator, these arms being preferably formed as guide vanes to co-operate with the helicoidal vanes 16 of the rotor; in order to protect the rotor against the entrance of flying bodies, a wire net 19a may be supported by brackets or arms 19 connected at their outer ends to the exhaust manifold and at the inner end to a hub enclosing a bearing 17 for the turbine shaft.

The air compressor 12 may be of any suitable type, for example centrifugal; it is preceded by an axial-type compressor with multiple rotors 20 and stators 21 inside an induction tube or shaft 22, to which the cold air is fed by the primary element consisting of the internal rotor vanes 16 already mentioned. The tube or casing 22, of diameter substantially equal at one end to that of the central portion of the rotor and at the other end to that of the compressor 12, surrounds the axial-type compressor 20, 21 upon the shaft 10 connecting the turbine rotor to the air compressor at the rear, this tube or casing being preferably made of or lined with thermally insulating material, as indicated at 24, to prevent undue heating of the incoming air by the combustion chambers 13 outside the tube or casing.

The centrifugal compressor 12 may be provided with two non-symmetrical working faces, the front one operating as main compressor in tandem with the axial compressor which delivers to it, and the rear face 25 operating in parallel as a separate source of compressed air, taking in air through suitable openings 26 at the rear end of the compressor casing; air may also be drawn through holes 27 in the shaft 10, adjacent to this rear face 25, the shaft being made hollow to admit air at one or both ends. The separately acting rear compressor 25 will of course be suitably dimensioned to give the desired capacity; the two deliveries of compressed air from the front and rear faces may be merged together at the periphery of the double-faced compressor 12, 25 before admission to the combustion chambers 13. As illustrated in Fig. 1, the compressor 12, 25 delivers into a manifold 28 having separate branches 28a leading to the respective combustion chambers, suitable baffles or deflectors 29 being provided inside the manifold to guide the compressed air into the breech ends of the chambers.

The one or more compressors may feed an annular combustion chamber, instead of the several separate combustion chambers 13 generally utilized, the chamber or chambers in the respective cases furnishing hot gases to drive the turbine rotor 11 at the forward end of the shaft 10.

The rear bearing 30 of the turbine shaft may be mounted in a plate 31 supported by brackets 32 from the body or casing of the compressor 12, beyond which the shaft extends to operate auxiliary equipment (not shown) such as mechanism for feeding the fuel to the combustion chamber or chambers, or any other devices that may be desired for the operation of an aircraft or for other purposes.

Since the primary compressor vanes 16 are effectively cooled by the incoming air, the central portion of the rotor 11 is maintained cold and therefore able to abstract heat from the turbine blades 15 exposed to the hot gases; in order to intensify the heat transmission from the hot turbine blades 15 to the cold vanes 16, their junctions are preferably in metallic continuity, for

example, they may be formed by segmental plates or platforms 33 integral with the blades and vanes. These platforms are assembled to constitute a complete annulus, of which a portion is shown in Figs. 2 and 3, the opposite edges of the platforms being engaged by clamping rings 34 of channel or V-section, held together by bolts 35 threaded into screwed nipples 36 of similar design to those employed on cycle wheel spokes. As seen in Fig. 1, the annulus formed by the assembled plates or platforms 33, with the clamping rings 34, fits into grooves 47 on the adjacent edges of the stator walls; further, on the side directed towards the exhaust, a thin lip 48 projects from the roots of the turbine blades 15 so as to overlap the grooved edge of the stator wall on this side. Due to the high velocity of the gases acting upon the turbine blades, leakage of the gases into the interior of the rotor, which would pollute and heat up the incoming air, is prevented by the frictionless glands provided by these means.

Each of the segmental plates or platforms 33 may be made integral with one turbine blade 15 and the corresponding vane 16, in order to secure the greatest possible conduction of heat between those parts; due to the contrary curvature of the blade and vane, as seen in Fig. 2, it may be necessary to give the platforms a rhomboid or non-rectangular shape, as shown in that figure.

Fig. 4 illustrates a modified form of platform 33 made integral with the respective turbine blade 15 and rotor vane 16, in which the oblique sides of the rhomboidal platform are castellated or provided with alternate projections and notches to interengage with the sides of the adjacent platforms; the ends of the platform may be made with square corners, as shown, and notched for lightness.

The inner ends or roots of the rotor spokes or vanes are mounted upon the shaft 10 by forming these roots 37 to a wedge-shape, as shown in Fig. 5, the angle between the opposite faces of each wedge being equal to the angular spacing of the vanes; for example, with seventy-two vanes, the included angle of each wedge will be five degrees. The wedges are arranged to engage at their inner ends with splines 38 upon the exterior of the shaft; as shown in Fig. 5, the splines are each of an angular extent of five degrees, the inner ends of alternate wedges resting upon the outer faces of the splines and those of the intermediate ones being made slightly longer in the radial direction so as to engage in the spaces between the splines, thus securing positive transmission of the rotary motion. The wedge-shaped roots 37 are clamped together by means of hub-plates 39; each of these plates is provided with circumferential grooves 40 on its inner face, the grooves fitting upon arcuate ribs 41 on the opposite faces of the wedges, and the plates being tightly held in engagement with the wedges, for example by pressure exerted along the shaft by a nut 42 securing the inner race of the bearing 17 (Fig. 1).

The invention procures a considerable economy of space and dimensions; the tubular casing 22, into the open front end of which the air enters by ram effect, with initial compression by the primary element constituted by the vanes 16 of the apertured rotor and further compression by the axial-type compressor 20, 21 inside the casing 22, is made convergent towards the main compressor 12 at the rear end, this main compressor being of relatively small diameter and capacity because of the reduction of volume of the air corresponding to its increased pressure due to the initial and

secondary compressions. The invention also furnishes a solution of the problem of cooling the turbine rotor (including the blades 15 exposed to the combustion gases), the driving shaft 10 and its bearings; it follows that at least the central portion of the turbine rotor can be constructed of steel or other material chosen solely from the point of view of its mechanical qualities, without regard to the questions usually involved by high temperature of operation. Where, however, some pre-heating of the air is desired, the thermal insulation of the casing 22 (such as indicated at 24) may be dispensed with, wholly or in part, in order to facilitate the transfer of heat from the combustion chamber or chambers 13.

The gases exhausted from the turbine may be collected in a manifold of annular form having one or more lateral outlets for discharging the gases rearwardly; Figs. 7 and 8 illustrate a manifold 43 fitted to the stator of the turbine, having two semi-annular branches of spiral shape leading to two outlets 44 which are united by a Y-pipe fitting 45 to deliver a single jet for the propulsion of the aircraft or the like. Alternatively, the exhaust gases may be led to suitable reaction devices, such devices being utilized for the propulsion of the aircraft or the like, as described in my prior U. S. Patent No. 2,224,260, dated December 10, 1940; an example of such reaction device, in which the gases are reversed through substantially 180 degrees by a deflecting surface, is hereinafter described with reference to Fig. 9.

The invention may be applied to gas turbines in general, apart from their employment for jet-propelled aircraft.

Fig. 9 illustrates the arrangement of a turbine differing slightly from that shown in Fig. 1, and having the forward end of the turbine shaft 110 fitted with suitable speed-reducing gear 101 for the driving of an airscrew 102, the air flowing from the screw entering with ram effect into the apertured central portion of the rotor 111; the rotor is provided with internal vanes 116 of helicoidal form, cooperating with stationary guide vanes 118 and constituting the primary element of an axial-type compressor with multiple rotors 120 and stators 121, inside a tubular casing 122, which delivers the compressed air to the intake of a main compressor 112 towards the rear end of the turbine shaft. This compressor feeds air through a manifold 128 into the breech ends of the combustion chambers 113 which are spaced in an annular series around the casing 122; a separately acting compressor 125 formed by the rear face of the main compressor delivers a supply of air through fuel injectors 103 into the breech ends of the combustion chambers, this fuel-injection air being drawn partly from the interior of the hollow shaft 110 by way of holes 127 near its rear end and to a much larger extent from the exterior, as hereinafter described, while the fuel is supplied by the auxiliary equipment 104 driven by the rear end of the turbine shaft. It will be noted that the rear compressor 125 feeds the combustion chamber burners directly with air conveying fuel from the injectors 103, while the main compressor 112 furnishes air through the manifold 128 at higher speed, at higher pressure and in greater quantity to maintain the flames in full activity.

The hot gases discharged from the combustion chambers 113 through the stator guide vanes 114 impinge upon the turbine blades 115 at the periphery of the rotor 111; these blades are preferably arranged for multi-stage expansion of the

gases, intermediate guide vanes 114a being provided between the stages, and the blades 115, 115a of the successive stages being of increasing height and external diameter to allow for the expansion of the gases, while at the same time increasing the centrifugal effect. After passing the final-stage blades 115a, the gases are reversed through substantially 180 degrees without shocks or eddies, but taking advantage of the outward diffusion or spread of the gases under centrifugal effect, by means of a curved deflecting surface 105; the latter, which serves as a reaction device to assist the propulsion of the aircraft, directs the gases rearwards over and between the combustion chambers 113, within the progressively expanding annular space between an outer cylindrical casing 106 and a slightly convergent partition 107 through which the combustion chambers extend, so that the gases flow along the gaps between the said chambers, the rear end of this partition being suitably apertured to allow passage of the compressed air to the injectors 103 and manifold 128. The said injectors and manifold are provided with external fins 108, in addition to internal deflectors 129, the whole of these fittings being preferably cast integrally in high-conductivity metal, so that a considerable and intensive heating of the compressed air is effected at this point by the high-speed gases returning over and between the combustion chambers 113, outside the partition 107. Such a heat-exchanger, with its external surfaces bathed or swept by very hot gases travelling at high speed, procures a much more efficient transfer of heat through the walls of the injectors and manifold than would their immersion in a hot gaseous medium of low speed or even stagnant.

From the moment when the hot gases have passed the finned injectors 103 fed by the rear compressor 125, they are directed into a jet device of the well-known kind, comprising two coaxial cones 109, 109a with a free space between them leading to a jet outlet 145 for the rearward discharge of the gases at high speed; the outer cone 109 forms a continuation of the casing 106, while the inner cone 109a forms a continuation of the partition 107, this inner cone or "bullet" enclosing the auxiliary equipment 104. The inner cone is stayed in relation to the outer cone by flared or stream-line webs 126, suitably heat-insulated, but instead of these webs being solid or closed at the ends, they are made hollow (as seen in section in the case of the uppermost one) to connect with openings through the two cones so that the external air can pass freely and substantially unheated to the intake of the rear compressor 125. The openings through the webs 126 may be made of sufficient size to allow access to the auxiliary equipment for the purpose of inspection and maintenance.

As in the case of the finned injectors 103 and manifold 128, the rotor 111 may be cast integrally with its rim 133, turbine blades 115 and compressor vanes 116, the whole being made of a high-conductivity metal to facilitate the transmission of heat from the blades to the vanes which are cooled by the air admitted through the rotor. The rim 133 fits into grooves 147 on the adjacent edges of the stator walls, providing a frictionless seal against leakage of the turbine gases to the interior of the rotor.

Due to the fact that the rearward flow of the exhaust gases from the deflecting surface 105, which itself produces a tractive force greater than the static thrust of the jet, takes place mainly in the gaps between the spaced combus-

tion chambers 213, the diameter of the outer casing 106 need be very little greater than the overall diameter of these chambers; consequently, the improved turbine presents the important advantage of relatively small external diameter, with resulting low weight, in addition to the advantages of superior cooling of the moving parts due to the admission of cold air through the apertured rotor, and that of fuel economy due primarily to the combination of a turbine-driven air-screw with the propulsive jet, and secondly to the preheating of the compressed air which is controlled by the design of the fins 108 and by the provision of heat-insulation at suitable points.

Fig. 10 illustrates the arrangement of a gas turbine according to the present invention as applied to the propulsion of an aircraft by a jet device 245 without the provision of an air-screw driven by the turbine shaft; in this case, the shaft 210 has the turbine rotor 211 mounted towards the rear end, and the double compressor 212, 225 mounted towards the front end, with the guide vanes 218 and the multiple rotors 220 and stators 221 of the axial-type compressor disposed along the shaft. The combustion chambers 213 are arranged in an annular series around the turbine, their rear ends being fitted with guide vanes 214 delivering the hot gases upon the turbine blades 215 integral with the rim 233 of the rotor; the exhaust gases are discharged to the jet device 245 by way of the free space between two coaxial cones 209, 209a.

The double compressor 212, 225 driven by the turbine shaft feeds the combustion chambers 213 in a similar manner to that described with reference to Fig. 9, the fuel being supplied by the auxiliary equipment 204 and the air for the compressor 225 being admitted partly through the hollow shaft by way of holes 227 and partly from the exterior through the intake openings 226. The main supply of air to the compressor 212 is admitted through the apertured rotor 211 having vanes 216 which form a primary element of the axial-type compressor; since, however, this rotor 211 is arranged at the rear end of the turbine, where the free admission of air is hindered by the inner cone or "bullet" 209a, the whole of the turbine is encased by a power egg or casing 206 having its forward end 207 left open and slightly flared so that the air enters by ram effect. The air passes over and between the injectors 203, manifold 228 and combustion chambers 213, all of which are suitably heat-insulated to prevent loss of heat to the incoming air; as the air travels along the interior of the casing 206, it moves clear of the combustion chambers 213 and flows outside the cone 209 at its junction with the turbine stator 205, beyond which the casing 206 is reduced in diameter, its rear end being suitably connected to the outer cone 209. A number of air ducts or inlets 230, of stream-line section, are carried through the cones 209, 209a, between the stator 205 and the rear end of the casing 206, the walls of these ducts acting to hold the two cones in relative position, while the passage ways through the ducts enable the air from the rear end of the casing 206 to pass inwards to the interior of the inner cone 209a and thus to reach the apertured rotor 211 with a considerable initial pressure due to the ram effect at the intake end 207 of the casing.

It will be noted that both air intakes are located at the normal or forward end of the turbine, where the auxiliary equipment 204 is installed, and that the incoming air is maintained

substantially unheated until it enters the compressors, heat-insulation being provided where necessary to prevent transfer to heat. The jet outlet 245 at the rear end may be arranged for a slight expansion of the gases under the effect of centrifugal force, by giving the outlet a slightly divergent shape, as indicated at 246. As in the previous examples of construction, the turbine rotor has its annular rim 233 fitting into grooves 247 on the adjacent edges of the stator walls, thus providing a frictionless seal to prevent leakage of the high-velocity gases from the combustion chambers into the interior of the rotor 211.

15 What I claim is:

1. A gas turbine comprising a rotor having peripheral blades, a hollow shaft driven by said rotor, a casing around said shaft, at least one combustion chamber furnishing hot gases, means for applying said gases to said blades in a direction parallel to said shaft for driving said rotor, a main compressor driven by said shaft for compressing air to feed said combustion chamber, said rotor and said main compressor being arranged towards opposite ends of said casing, and an axial-type compressor with multiple rotors and stators inside said casing, said first-mentioned rotor being apertured to admit cold air to said axial-type compressor, and said axial-type compressor forcing the air to said main compressor in a direction opposite to the flow of said gases past said blades, in combination with another compressor driven by said shaft and drawing cold air through said hollow shaft, said other compressor feeding air to at least one combustion chamber furnishing hot gases to drive said first-mentioned rotor.

2. A gas turbine comprising a rotor having peripheral blades, a hollow shaft driven by said rotor, a casing around said shaft, at least one combustion chamber furnishing hot gases, means for applying said gases to said blades in a direction parallel to said shaft for driving said rotor, a main compressor driven by said shaft for compressing air to feed said combustion chamber, said rotor and said main compressor being arranged towards opposite ends of said casing, said combustion chamber being located between said compressor and said blades, and an axial-type compressor with multiple rotors and stators inside said casing, said first-mentioned rotor being apertured to admit cold air to said axial-type compressor, and said axial-type compressor forcing the air to said main compressor in a direction opposite to the flow of said gases past said blades, in combination with another compressor driven by said shaft and drawing cold air through said hollow shaft, said other compressor being non-symmetrical in relation to said main compressor, said axial-type and main compressors operating in series, and said other compressor operating in parallel to said series-operating axial-type and main compressors.

3. A gas turbine for the propulsion of vehicles including aircraft, comprising a rotor having peripheral blades, a shaft driven by said rotor, a plurality of combustion chambers furnishing hot gases, means for applying said gases to said blades for driving said rotor, an axial-type compressor and two centrifugal compressors, all said compressors being driven by said shaft for compressing air to feed said combustion chambers, said rotor being arranged towards the rear end of said shaft, said centrifugal compressors being arranged towards the forward end of said shaft,

said rotor being apertured for passage of cold air in a forward direction to said axial-type compressor; a manifold of annular form collecting the exhaust gases flowing in a rearward direction from said rotor blades, and at least one outlet from said manifold for discharging the exhaust gases rearwardly of the vehicle.

4. A gas turbine for the propulsion of vehicles including aircraft, comprising a rotor having peripheral blades, a hollow shaft driven by said rotor, a plurality of combustion chambers furnishing hot gases, means for applying said gases to said blades for driving said rotor, an axial-type compressor, a main centrifugal compressor and another centrifugal compressor, all said compressors being driven by said shaft for compressing air to feed said combustion chambers, part of said air being drawn through said hollow shaft, said rotor being arranged towards the rear end of said shaft, said centrifugal compressors being arranged towards the forward end of said shaft, said rotor being apertured for passage of cold air in a forward direction to said axial-type compressor, a manifold of annular form collecting the exhaust gases flowing in a rearward direction from said rotor blades, said manifold having two semi-annular branches of spiral shape, two outlets from said branches, and means for combining the gases discharged through said two outlets to deliver a single rearwardly directed jet for the propulsion of the vehicle.

5. A gas turbine for the propulsion of vehicles including aircraft, comprising a rotor having peripheral blades, a shaft driven by said rotor, a plurality of combustion chambers furnishing hot gases, means for applying said gases to said blades for driving said rotor, an axial-type compressor and two centrifugal compressors, all said compressors being driven by said shaft for compressing air to feed said combustion chambers, said rotor being arranged towards the forward end of said shaft, said centrifugal compressors being arranged towards the rear end of said shaft, said rotor being apertured for passage of cold air in a rearward direction by ram effect to the intake of said axial-type compressor, a curved deflecting surface for reversing the forwardly exhausting gases from said rotor blades and directing said gases rearwardly between said combustion chambers, and means for collecting said rearwardly directed gases to deliver a rearward jet for the propulsion of the vehicle.

6. A gas turbine for the propulsion of vehicles including aircraft, comprising a rotor having peripheral blades, a shaft driven by said rotor, a plurality of combustion chambers furnishing hot gases, means for applying said gases to said blades for driving said rotor, an axial-type compressor and two centrifugal compressors, all said compressors being driven by said shaft for compressing air to feed said combustion chambers, said rotor being arranged towards the forward end of said shaft, said centrifugal compressors, being arranged towards the rear end of said shaft, said rotor being apertured for passage of cold air in a rearward direction by ram effect to the intake of said axial-type compressor, a curved deflecting surface for reversing the forwardly exhausting gases from said rotor blades and directing said gases rearwardly past said combustion chambers, means for effecting heat-exchange between said rearwardly directed gases and the air fed to said combustion chambers by said centrifugal compressors, and means for collecting said rearward-

ly directed gases to deliver a rearward jet for the propulsion of the vehicle.

7. A gas turbine for the propulsion of aircraft, comprising a rotor having peripheral blades arranged for at least two stages of gas expansion, a hollow shaft driven by said rotor, a plurality of spaced combustion chambers furnishing hot gases, means for applying said gases to said blades for driving said rotor, an axial-type compressor and two centrifugal compressors driven by said shaft for compressing air to feed said combustion chambers, part of said air being drawn through said hollow shaft, said rotor being arranged towards the forward end of said shaft, said centrifugal compressors being arranged towards the rear end of said shaft, an airscrew at the forward end of said shaft, said airscrew being driven by said shaft, said rotor being apertured for passage of cold air from said airscrew in a rearward direction to the intake of said axial-type compressor, a curved deflecting surface receiving the forwardly exhausting gases from said rotor blades, said deflecting surface being adapted to reverse the flow of said gases by taking advantage of their outward diffusion under centrifugal effect and to direct them rearwardly around said combustion chambers, an outer casing around said combustion chambers, said casing being adapted to enclose said rearwardly directed gases and to force them into the gaps between said spaced combustion chambers, and means for collecting the gases rearwards of said combustion chambers to deliver a single jet for the propulsion of the aircraft.

8. A gas turbine for the propulsion of aircraft, comprising a rotor having peripheral blades, a hollow shaft driven by said rotor, a plurality of combustion chambers arranged in an annular series around said shaft, means for applying hot gases from said combustion chambers to said blades in a direction parallel to said shaft for driving said rotor, means for collecting the gases in rear of said blades to deliver a jet for the propulsion of the aircraft, an axial-type compressor and two centrifugal compressors, all said compressors being driven by said shaft for compressing air to feed said combustion chambers, part of said air being drawn through said hollow shaft by one of said centrifugal compressors, said rotor being arranged towards the rear end of said shaft, said centrifugal compressors being arranged towards the forward end of said shaft, said rotor being apertured for passage of air in a forward direction to the intake of said axial-type compressor, an outer casing around said combustion chambers, the forward end of said casing being open for admission of cold air by ram effect, said air flowing along the gaps between said combustion chambers, and passages leading from the rear end of said casing to convey said air to said apertured rotor, said passages extending transversely through said collecting means.

9. A gas turbine comprising a rotary shaft, an axial-type compressor with multiple rotors and stators, the rotors of said compressor being driven by said shaft, a stator element at the inlet end of said compressor, a rotor element adjacent to said stator element, said rotor element including turbine blades upon its periphery and helicoidal spokes secured to said shaft, two centrifugal compressors driven by said shaft and located at the other end of said axial-type compressor, said helicoidal spokes co-operating with said stator element to force air into said axial-type compressor for feeding one of said centrifugal compressors, combustion chambers arranged to re-

ceive air from said centrifugal compressors and to furnish hot gases of combustion, and means for applying said hot gases to said turbine blades for driving said rotor element and shaft, the direction of said hot gases in relation to said rotor element being opposite to the direction of said air in relation thereto.

10. A gas turbine comprising a rotary shaft, an axial-type compressor with multiple rotors and stators, the rotors of said compressor being driven by said shaft, a stator element at the inlet end of said compressor, a rotor element adjacent to said stator element, said rotor element including peripheral turbine blades integral with helicoidal spokes secured to said shaft, two centrifugal compressors driven by said shaft and located at the other end of said axial-type compressor, said helicoidal spokes co-operating with said stator element to force air into said axial-type compressor for feeding one of said centrifugal compressors, combustion chambers arranged to receive air from said centrifugal compressors and to furnish hot gases of combustion, and means for applying said hot gases to said turbine blades for driving said rotor element and shaft, the direction of said hot gases in relation to said rotor element being opposite to the direction of said air in relation thereto.

11. A gas turbine comprising a rotary shaft, an axial-type compressor with multiple rotors and stators, the rotors of said compressor being driven by said shaft, a stator element at the inlet end of said compressor, a rotor element adjacent to said stator element, said rotor element including turbine blades upon its periphery and helicoidal spokes secured to said shaft, two centrifugal compressors driven by said shaft and located at the other end of said axial-type compressor, said helicoidal spokes co-operating with said stator element to force air into said axial-type compressor for feeding one of said centrifugal compressors, combustion chambers arranged to receive air from said centrifugal compressors and to furnish hot gases of combustion, and means for applying said hot gases to said turbine blades for driving said rotor element and shaft, said gas-applying means including baffles for preventing leakage of said hot gases adjacent to said rotor element into the air forced into said axial-type compressor, and the direction of said hot gases in relation to said rotor element being opposite to the direction of said air in relation thereto.

12. A gas turbine comprising a hollow rotary shaft, an axial-type compressor with multiple rotors and stators, the rotors of said compressor being driven by said hollow shaft, a stator element at the inlet end of said compressor, a rotor element adjacent to said stator element, said rotor element including turbine blades upon its periph-

ery and helicoidal spokes secured to said shaft, two centrifugal compressors driven by said shaft and located at the other end of said axial-type compressor, one of said centrifugal compressors drawing air through one end of said hollow shaft, the other of said centrifugal compressors receiving air from said axial-type compressor, said helicoidal spokes co-operating with said stator element to force air into said axial-type compressor, combustion chambers arranged to receive air from said centrifugal compressors and to furnish hot gases of combustion, and means for applying said hot gases to said turbine blades for driving said rotor element and shaft, the direction of said hot gases in relation to said rotor element being opposite to the direction of said air in relation thereto.

13. A gas turbine comprising a hollow rotary shaft, an axial-type compressor with multiple rotors and stators, the rotors of said compressor being driven by said hollow shaft, a stator element at the inlet end of said compressor, a rotor element adjacent to said stator element, said rotor element including turbine blades upon its periphery and helicoidal spokes secured to said shaft, a centrifugal compressor driven by said shaft and located at the other end of said axial-type compressor, said helicoidal spokes co-operating with said stator element to force air into said axial-type compressor for feeding said centrifugal compressor, another centrifugal compressor driven by said shaft and located back-to-back of said first-mentioned centrifugal compressor, said other centrifugal compressor drawing air through one end of said hollow shaft, at least one combustion chamber arranged to receive air from said centrifugal compressors and to furnish hot gases of combustion, and means for applying said hot gases to said turbine blades for driving said rotor element and shaft, the direction of said hot gases in relation to said rotor element being opposite to the direction of said air in relation thereto.
